VENTILATOR

Marion G. Roberts, Parkersburg, W. Va., assignor
to The Airolite Company, Marietta, Ohio, a corporation of Ohio

Application March 25, 1948, Serial No. 17,010

5 Claims. (Cl. 98—121)

1

This invention has relation to a ventilator, useful for many purposes, but designed to be especially useful as a closure for transoms, doorways, windows, panels, or the like.

An object of the invention is to provide a ventilator of the general character as hereinafter set forth wherein will be incorporated desirable, novel and improved features and characteristics of construction.

A further object is to provide a ventilator of simple and inexpensive construction which will be an improvement over ventilators heretofore in commerce employed for the same general purpose.

A further object is to provide a ventilator which will consist of a frame having a plurality of louvers mounted therein, and will incorporate a new and improved construction and arrangement adapted to render the ventilator capable of being shipped knocked down and assembled on the job.

A further object is to provide a ventilator which will consist of a frame, louver supporting elements assembled with said frame, louvers adapted to be adjustably mounted upon said supporting elements, and a novel and improved construction and arrangement adapted to render parts of the ventilator capable of being shipped knocked down and assembled together while being installed in a building.

And a further object is to provide a ventilator incorporating a new and improved construction and arrangement adapted to render the parts of the ventilator capable of being fabricated at a factory, shipped unassembled and assembled together concurrently with performance of installation of said ventilator in a building.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible as long as within the spirit of the invention and the scope of the claims which follow.

In the accompanying drawings forming a part of this specification,

Fig. 1 is an exterior elevational view, partially broken away, of a ventilator made according to the invention;

Fig. 2 is a vertical sectional view, taken on line 2—2 in Fig. 1;

2

Fig. 3 is a horizontal sectional view, taken on line 3—3 in Fig. 1;

Fig. 4 is an enlarged perspective view of a supporting element for louvers of the ventilator; and

Fig. 5 is a detail sectional view of a modification.

The improved ventilator herein illustrated and described is constituted as a frame of rectilinear configuration, spaced apart supporting elements assembled with said frame, supporting brackets adapted to be adjustably mounted upon said supporting elements, and louvers assembled with said supporting brackets.

10 The frame, as shown, is composed of sheet metal. It includes a top member 10, a bottom member 11 and side members 12 and 13. The top member 10 is constituted as a plate having downwardly extending, interior and exterior flanges, the bottom member 11 is constituted as a plate having an upwardly extending interior flange and a downwardly extending exterior flange, and each of the side members 12 and 13 is constituted as a plate having an inwardly 25 extending, interior flange and an outwardly extending, exterior flange. Meeting end portions of the top and bottom members 10 and 11 and the side members 12 and 13 may be in overlapping relation.

15 The spaced apart supporting elements of the ventilator are constituted as vertically disposed metallic pipes or rods, each denoted 14, having their upper ends secured to the top member 10 of the frame and their lower ends secured to the bottom member 11 of said frame. Each pipe or rod 14 is of uniform diameter throughout its entire length, and the upper and lower end portions of said pipes or rods are removably fitted to annular elements 15 which are themselves secured, 30 as at 16, to said top and bottom frame members. And, too, the pipes or rods 14 are of equal diameter.

25 The supporting brackets of said ventilator, each indicated 17 and one disclosed in detail in Fig. 4 of the drawings, are each constituted as a collar 18, of size to be snugly slidable along the pipes or rods 14, and a louver supporting member 19 integral or rigid with said collar and situated at the exterior side thereof. A set screw 20 in each 35 collar 18 is adapted to be turned home against the pipe or rod upon which the collar is situated to fasten said collar in fixed relation to said pipe or rod and loosened to permit the collar to be slid longitudinally of the pipe or rod.

55 As disclosed in Figs. 1 to 4 of the drawings,

each louver supporting member 19 consists of a radially extending web 21 integral or rigid with the collar 18 of the corresponding supporting bracket 17 and an obliquely disposed stepped portion, integral or rigid with the web, providing upper and lower substantially parallel, downwardly and exteriorly extending ledges, designated 22 and 23, respectively. A first attachment piece upon and extending upwardly from the upper edge of each upper ledge 22 is denoted 24, a flange upon and extending exteriorly from the upper edge of each attachment piece 24 is indicated 25, and a second attachment piece upon and extending downwardly from the lower edge of each lower ledge 23 is represented 26.

As shown in Fig. 5, the louver supporting member consists of a radially extending web 27 on the collar 18 and a single downwardly and exteriorly extending ledge 28 on the web 27. Attachment pieces 29 and 30 on the ledge 28 are equivalent to the attachment pieces 24 and 26, and a flange 31 on the attachment piece 29 is equivalent to the flange 25.

The louvers of the ventilator desirably can be composed of metal, as can also the supporting brackets, and as shown said louvers are disposed in horizontal planes and parallel relation.

As disclosed in Figs. 1 to 3, upper louvers 32 are supported upon upper ledges 22 of horizontally aligned supporting members 19, lower louvers 33 are supported upon lower ledges 23 of horizontally aligned supporting members 19, and lower portions of the upper louvers 32 are in overlapped relation to upper portions of the lower louvers 33. A first attachment piece 34 upon and extending upwardly from the upper edge of each upper louver 32 is secured, as at 35, to and against first attachment pieces 24 on upper ledges 22 of supporting brackets 17 which are in the same horizontal plane, and a second attachment piece 36 upon and extending downwardly from the lower edge of each lower louver 33 is secured, as at 37, to and against second attachment pieces 26 on lower ledges 23 of supporting brackets 17 which are in the same horizontal plane. In the disclosure as made, lower portions of lower louvers 33 are in overlying, exteriorly spaced relation to upper portions of adjacent upper louvers 32 just beneath, the upper portion of the uppermost upper louver 32 is situated below the body of the top frame member 10 between its downwardly extending interior and exterior flanges, and a lower portion of the lowermost louver 33 is at about the elevation of and disposed exteriorly of the bottom frame member 11.

As shown in Fig. 5, a single louver 38 is supported upon the single ledge 28, and in an installation including louvers as in said Fig. 5 lower portions of upper louvers 38 desirably will overlie and be in exteriorly spaced relations to upper portions of lower louvers 38. Attachment pieces 39 and 40 on single louvers such as 38 when employed will be secured to and against attachment pieces such as 29 and 30 upon the members by which said single louvers are supported.

In the illustrated embodiment of the invention, the louvers span the distance between adjacent supporting brackets 17, adjacent horizontally aligned louvers meet at the midlengths of the ledges 22 and 23 of the central supporting brackets, and outer end portions of said louvers terminate in proximate relation to the side frame members 12 and 13. It will be apparent that each of the louvers could be constituted as a single length spanning the distance between said

side frame members. Also it will be apparent that the ventilator can incorporate louvers of various different types and configurations.

The parts of the ventilator can be fabricated at a factory, shipped knocked down and assembled in the field.

In the accomplishment of installation of the ventilator, the top, bottom and side frame members will be fitted to an opening in a building and fastened in place in any suitable and convenient manner, as by screws, nails, screw bolts, etc. The supporting brackets 17 will be placed upon the supporting rods or pipes 14, and, after said supporting brackets are applied, said supporting rods or pipes will be assembled with the frame and building in the manner as disclosed in the drawings. The means which fastens the annular elements 15 to the top and bottom frame members 10 and 11 also will enter the structure of the building. The louvers desirably will be assembled with the supporting brackets after these have been adjusted to preferred locations on the vertical rods or pipes. Lower louvers 33 preferably will be placed in position before adjacent upper louvers 32 are applied.

Attention is called to the fact that the ventilator herein illustrated and described has no mullions. An exterior view of said ventilator presents continuous horizontal lines.

What is claimed is:

1. A ventilator comprising a rectilinear frame, including spaced horizontal top and bottom frame members to be mounted in an opening in a wall, spaced vertical cylindrical rods, annular retaining elements removably mounted on opposite end portions of said rods, means for securing said annular retaining elements in engaged relation with the top and bottom frame members and for fixing said rectilinear frame in said opening constituted as fasteners to be passed through the annular retaining elements and the top and bottom frame members and anchored in portions of said wall bounding upper and lower portions of said opening, supporting brackets each constituted as a collar removably mounted on one of the rods for slidable and rotatable adjustment and a louver supporting member rigid with said collar, and means for independently fastening each of said collars in fixed relation to its corresponding rod.

2. A ventilator comprising a rectilinear frame including spaced horizontal top and bottom frame members to be mounted in an opening in a wall, spaced vertical cylindrical rods, annular retaining elements removably mounted on opposite end portions of said rods, means for securing said annular retaining elements in engaged relation with the top and bottom frame members and fixing said rectilinear frame in said opening constituted as fasteners to be passed through the annular retaining elements and the top and bottom frame members and anchored in portions of said wall bounding upper and lower portions of said opening, supporting brackets each constituted as a collar removably mounted on one of the rods for slidable and rotatable adjustment, a louver supporting member having a louver supporting surface inclining outwardly and downwardly from the axis of said collar and a web rigidly connecting said louver supporting member to said collar and lying in a plane passing through said collar axis perpendicular to said louver supporting surface, and means for independently fastening each of said collars in fixed relation to its corresponding rod.

3. A ventilator comprising a rectilinear frame including spaced horizontal top and bottom frame members to be mounted in an opening in a wall, a vertical cylindrical rod, annular retaining elements removably mounted on opposite end portions of said rod, means for securing said annular retaining elements in engaged relation with the top and bottom frame members and for fixing said rectilinear frame in said opening constituted as fasteners to be passed through the annular retaining elements and the top and bottom frame members and anchored in portions of said wall bounding upper and lower portions of said opening, supporting brackets each constituted as a collar removably mounted on said rod for slidable and rotatable adjustment and a louver supporting member rigid with said collar, and means for independently fastening each of said collars in fixed relation to the rod.

4. A ventilator for installation in a rectangular opening in a wall including a rectangular frame contiguous with portions of said wall bounding said rectangular opening and comprising a channel-shape top member, a Z-shape bottom member and two Z-shape side members, said top, bottom and side members each having an inner flange parallel to and adjacent an inner surface of said wall and extending from the periphery of said rectangular opening at said inner surface toward the center of said opening, said bottom and side members each having an outer flange opposite said inner flange parallel to and contiguous with an outer surface of said wall extending from the periphery of said rectangular opening away from said opening, spaced apart vertical rods mounted rigidly with respect to top and bottom portions of said wall bounding said rectangu-

lar opening, louver supporting members mounted on said vertical rods, a plurality of horizontally extending louver units fastened to said louver supporting members at a side thereof adjacent said outer surface of said wall and extending continuously between said side frame members, a louver unit extending from a position inwardly of and higher than a next higher louver unit to a position outwardly of and lower than a next lower louver unit.

5 The combination as specified in claim 4 wherein said top member is made up of a plurality of contiguous channel-shape elements, said bottom and side members are each made up of a

15 plurality of contiguous Z-shape elements, said louver units are constituted as a plurality of contiguous louver elements, and wherein a louver supporting member is in contiguous backing relation to each pair of adjoining, contiguous louver

20 elements at the point of contact between said elements.
